UNITED STATES PATENT OFFICE.

HALVER R. STRAIGHT, OF ADEL, IOWA.

CONTINUOUS-PUGGING WET PAN.

Application filed June 23, 1924. Serial No. 721,850.

The object of my invention is to provide improvements in mechanisms for preparing and working clay in the nature of a continuous pugging wet pan adapted to feed the pugged material to one or a number of tile machines simultaneously.

A further object is to provide an improved pugging mechanism so arranged that the clay or shale to be pugged may be worked intermittently, as I find this has considerable advantage in giving the material more time to thoroughly mix with the water, and at the same time enable the device to be operated more economically from a power standpoint, the object being to pug or agitate the material for a short time, then permit it to rest for a short time while the moisture is being absorbed by the drier portions of the material broken up by the pugging action, thereby saving a considerable power over the continuous method of pugging.

A further object is to provide in such a device, means whereby a series of tile machines may be simultaneously fed from the wet pan of the pugging mechanism, each of said tile machines being adapted to be independently thrown into and out of operation relative to said pan, and each of said tile machines being operatively connected with an independent pugging apparatus including a water supply, the last said devices being so constructed and arranged that as the tile machine is thrown out of operation, the said water supply and pugging apparatus will also be thrown out of operation.

A further object is to provide means for automatically controlling the amount of water fed to the mixture within the pan.

A further object is to provide in connection with such a device, that type of a tile machine having continuously operated wire cutters, and in connection with said wire cutters, means whereby, if one of the cutters should become broken, the tile machine together with its pugging unit will be automatically thrown out of operative relation with the pugging pan.

A further object is to provide in a pugging mill an improved blunger knife.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a plan view of a segmental portion of my improved device.

Figure 2 is an enlarged, detail, segmental, sectional view taken on the line 2—2 of Figure 1.

Figure 3 is an enlarged, detail, sectional view taken on the line 3—3 of Figure 1.

Figure 4 is an enlarged, detail, sectional view taken on the line 4—4 of Figure 1.

Figure 5 is a detail, sectional view taken on the line 5—5 of Figure 4.

Figure 6 is a sectional view taken on the line 6—6 of Figure 1.

Figure 7 is a detail, sectional view taken on the line 7—7 of Figure 1.

Figure 8 is a side elevation of a tile cutter frame, such as commonly used on tile cutting machines, showing the manner in which my improved automatic control is connected therewith.

Figure 9 is a side elevation of one of the cutter arms.

Figure 10 is a diagram of the electric circuits used in connection with my improved device.

Figure 11 is a detail side elevation of one of the blunger knives.

My improved device is supported on a foundation 10 which is provided with a pivot member 11 designed to support a vertically arranged pivot 12, said pivot having mounted thereon a horizontally arranged circular fed table 13. The said table 13 is provided at its central portion with a downwardly extending sleeve 14 supported on the shaft 12. Each edge of the table 13 is provided with a downwardly extending cylindrical wall member 15, the lower edge of which terminates in an annular bottom member 16. The outer edge of the member 16 is provided with upwardly extending annular flange 18, the lower edge of said flange being provided with an annular track member 19 having its under surface beveled and designed to be carried and supported by means of a series of rollers 20 supported on a shaft 21 arranged radially with the center of the shaft 12.

The walls 15 and 18 and the bottom member 16 form an annular pan, which I shall term the wet pan adapted to be rotated in a horizontal plane about the pivot 12. This rotary movement is imparted to the said pan by connecting one of the shaft members 21 with a speed reducing member 22 operated from an electric motor 23, the pan being

driven through the frictional engagement between the roller 20 and the track 19.

Mounted above the fed table 13 is a hopper 24 having a conical bottom member 25 provided with an opening 26. The lower edge of the member 25 terminates at a slight distance above the table 13, and the opening 26 being of a diameter less than the diameter of said plate 13, so that pulverized clay or shale may be fed to the table 13 without running over its outer edge by gravity.

The lower edge of the member 25 is provided with a series of outwardly and downwardly extending bracket members 27, the lower end of which is provided with a bearing member 28. Each of the bearing members 28 is provided with a radially arranged shaft 29 which extends outwardly above and beyond the wall member 18. The outer end 20 of each of the shafts 29 is operated through a speed reducing gear device 30, and each of said gear devices being operated through an electric motor 31. This provides means whereby the shaft 29 may be continuously 25 rotated through the motor 31 and the speed reducing mechanism 30.

Each of the shafts 29 is provided with a series of blunger knives 32, said knives being arranged in a common plane with each 30 alternate knife extending in the opposite direction from the intermediate knives, so that when the shaft 29 is inoperative, the knives 32 may be moved to a horizontal plane, permitting any material in the wet pan to move 35 freely beneath them. Each of said knives 32 has its outer end provided with a circular face 33, which is slightly eccentric with the shaft 29, so that as the knife is rotated at a speed slightly different from the speed of 40 the bottom member 16, a squeezing and pulling action will take place, causing the particles of material to be more thoroughly pulled apart and mixed.

The inner face of each of the knives is 45 beveled at 34 so that as the shaft 29 is rotated, material within the pan will be moved slightly outwardly. I have preferably provided four of the shafts 29 arranged in a radial manner and equal distances apart.

50 Between each pair of shafts 29 and outside of the flange 18, I have provided a tile machine 35, the axis of which is also placed radially with the center of the shaft 12, as clearly shown in Figure 1. Each of the tile machines is provided with a feed auger 36 and a feed hopper 37, the inner end of the hopper 37 rests substantially adjacent to the outer face of the flange 18.

Adjacent to one side of the hopper 37, I 60 have provided a casing 38 in which is mounted a shaft 39. The outer end of the shaft 39 adjacent to the hopper 37 is provided with a plow blade 40 so arranged that as the shaft 39 is rocked, the blade 40 may be moved into 65 and out of position within the pan. The

edge 41 of said blade is designed to rest adjacent to the upper face of the member 16 when in an operative position, and to deliver material from the pan to the hopper 37 in a manner similar to that of the ordinary 70 plow.

That portion of the shaft 39 within the casing 38 is provided with a segment 42, the upper edge of which is provided with a lug 43 and a notch 44. The notch 44 is designed to receive one end of a latching member 45 pivoted at 46 and having a downwardly extending arm 47. The free end of said arm is pivotally connected to a control rod 48. The latch 45 is designed to suspend 80 the plow 40 in its elevated position.

Thus it will be seen that if the control rod 48 is manually moved outwardly, the latch 45 will be lifted from engagement with the notch 44, which in turn will permit the segment 42 to swing in an anti-clockwise direction as illustrated in Figure 4, and the plow member 40 to be dropped into position within the pan. A spring 49 is provided on the rod 48 for yieldably holding the latch 45 in 90 the notch 44. The casing 38 is provided with an electric magnet 50 having a sliding core 51, one end of said core being pivotally connected to the sector 42. This provides means whereby the plow may be lifted by establishing an electric circuit through the magnet 50, the purpose of which will hereinafter be made clear.

A switch device 52 is also provided in the casing 38 comprising a bracket 53 having a stationary contact member 54 and a movable contact member 55. This member 55 is actuated by means of a pivoted lever 56, the lower end of which is designed to engage the lug 43 when the plow is in its inoperative 100 position, thereby causing the switch member 55 to disengage the switch member 54, through the action of a coil spring 57. A spring 58 is provided for moving the switch device 55 to its closed position. The switch 105 52 is included in a circuit hereinafter described.

The pan is also provided with a number of muller wheels 59, each of which is mounted on a shaft 60, each of said shafts being supported in pivoted arms 61. The said arms 61 are carried by a shaft 62 mounted in suitable brackets 63 and 64. The axis 60 is also arranged substantially radially with the shaft 12.

115 Adjacent to one side of each of the mullers 59 is a vertically arranged water supply pipe 65, the lower end of each of said pipes being provided with a control valve 66, each of said valves having a stem 67 operated through a bell crank lever 68. One end of the bell crank lever 68 is provided with a magnet core 69 designed to slide in the electromagnet 70. A spring 71 is provided for holding the core 69 to its outer 120 125 130

limit of movement, and also for closing the valve 66.

Each of the brackets 28 is provided with a forwardly extending portion 72, to which is pivoted a scraper blade 73, the said blades being designed to extend inwardly and forwardly adjacent to the top face of the table 13, so that as the said table is rotated, material thereon will be scraped into the pan. A rod 74 is pivoted near the pivot end of each of the members 73, and is designed to extend outwardly into the casing 38. The outer end of said rod 74 is pivoted to the sector 42, as clearly shown in Figure 4.

By this arrangement, it will be seen that as the plow 42 is elevated, the rod 74 will be moved outwardly, which in turn will cause the scraper 73 to be swung outwardly from the table 13, thereby providing means whereby the feeding of the material to the pan will be automatically cut off.

I have provided in the rod 74 a turn buckle 75 to provide means for shortening and lengthening the shaft 74, which in turn provides means for adjusting the amount of material fed by the member 73.

Pivots mounted on the end of each of the shafts 62 I have provided a packer member 76 which extends slightly downwardly into the pan and terminates in a horizontal and rearwardly extending portion in front of the plow 40.

Pivots mounted adjacent to the front side of the hopper 37 is a shaft 77, the inner end of which is provided with a crank wheel 78 having a crank pin 79 designed to carry a connecting rod 80, the lower end of which is pivotally connected to upwardly extending lugs 81 from the free end of the packer 76.

Thus it will be seen that if the shaft 77 is rotated, the free end of the packer will be elevated and lowered, which will cause the pugged material to be packed ahead of the plow, so as to form a sort of stiff column of clay, which may be easily and readily slid upwardly and outwardly over the face of the plow into the hopper 36, which would be almost impossible if the material were loose at the time it engaged the plow.

The shaft 77 is driven from an electric motor 82 and worm gears 83.

The inner end of each of the speed reducing gear members 30 is provided with an annular contact ring 84, which is insulated from the casing of the speed reducer, and designed to form one terminal of an electric circuit. The annular member 84 is provided with a segment 85 mounted on one end of a slidable shaft 86, so arranged that as the said shaft is moved longitudinally, the sector 85 will be moved into and out of position in the annular ring 84, and when in position forms a part of the contact.

Mounted on the shaft 29 is a hub 87 having an outwardly extending arm 88, the said

arm being provided with a pivoted contact member 89, which is held outwardly by means of a spring 90, and into contact with the members 84 and 85. The purpose of this will hereinafter be made clear.

In Figures 8 and 9, I have illustrated the cutter reel of the tile machine, which comprises an axle 91 having a spider 92 designed to carry a series of pivoted cutting arms 93, each of said arms being provided with a cutting wire 94. The said wire 94 is mounted in insulated supporting members 95, 96 and 97. The members 96 and 97 are electrically connected by conductors 98. One of the members 98 is connected with a slip ring 99, which is insulated from the spider 92. A contact member 100 is provided for said ring, which is connected to a conductor 101 of an electric circuit.

Thus it will be seen that an electric circuit may be established through the conductors 98 and the cutting wires 94, and the opposite one of the members 98 being grounded to the spider 92, which in turn is grounded to the conductor 102. It will be seen that if any one of the wires 94 should become broken, then the circuit maintained in the conductors 101 and 102 will be broken.

The conductor 102 is connected with a supply conductor 103, which has included a switch 104, which makes contact with a supply conductor 105. The opposite supply conductor 106 has a switch 107 which is connected to a conductor 108. The conductors 105, 103 and 108, together with the switches 104 and 107, provide means whereby an electric current may be supplied from any suitable power plant for the operation of the motors and electric mechanism of my improved device.

The conductor 101 has included a relay coil 109, said relay being provided with a contact 110 included in an electric conductor 111 connected with the conductor 103. The conductor 111 is connected at one side of the plow operating magnet 50, while the other side of the magnet 50 leads to the switch member 54, while the switch member 55 is provided with a conductor 112 leading to the conductor 108.

Thus it will be seen that when the cutter wires 94 are placed in position, and the switches 104 and 107 are closed, a current will flow through the said cutter wires 94 and through the relay coil 109, which is preferably of high resistance, so that a small amount of current is consumed. This will cause the switch device 110 to be normally held open and the plow will then be free to drop into position within the pan when the control rod 48 has been operated, but if one of the wires 94 should become broken, then the switch lever 110 will be released from the coil 109 and a circuit

established through the conductor 111, which will energize the coil 50, and cause the plunger 51 to be drawn inwardly and the plow elevated with the latch 45 engaging the notch 44. The lug 43 will then engage the lower end of the lever 56 and cause the switch member 55 to disengage the switch member 54, again opening the circuit.

10 This provides means whereby the plow will be automatically elevated in case one of the wires 44 of the corresponding cutter is broken.

15 The motors 23 and 31 are provided with a conductor 113 connected with the conductor 103. The motor 23 is provided with a conductor 114 connected with the conductor 108, while the motor 31 is provided with a second conductor 115 connected with the 20 segment 84, while the contact 89 is provided with a conductor 116, which includes the coil of the magnet 70. The said magnet 70 is connected with the conductor 114, thereby establishing a circuit from the conductor 25 114 through the coil 70, the conductor 116, the contact 89, the segment 84 and the conductor 115.

30 The shaft 39 is provided with a cam 117 designed to coact with the roller 118 on one end of the shaft 86, so arranged that when the plow 40 is in its elevated position, the segment 85 will be disengaged from the segment 84, and contact broken between the member 89 and the said segment 85, when 35 the knives 32 are in a horizontal position, as clearly shown in Figure 6.

40 Thus it will be seen that when the plow 40 is moved to its elevated position, the circuit through the motor 31 and the conductor 116 will be broken at the time the knives 32 are in a horizontal position, thereby causing the said pug shaft 29 to be stopped in said position, and also causing the coil 70 to become de-energized, permitting the spring 71 to move the valve 66 to a closed position and the water supply for that particular unit cut off.

45 In this connection, it should be noted that the coil 70 is wound of low resistance, and is in series with the conductor which supplies current to the motor 31. The tension of the spring 71 is so adjusted that the core 69 rests in a balanced condition between the spring 71 and the magnetic pull on the core 69, to move it to an open position.

50 By the proper adjustment of the coil 61, it will be seen that the said coil may be made to provide an automatic relation of the water supply, due to the variation in the current supplied to the motor, the said variation of current being in direct proportion to the amount of energy required to rotate the pugging shaft. If the material within the pan is stiff, then a considerable 55 energy is required to impart rotation to the

shaft, which in turn will require a heavy load on the coil 70, and in turn cause the valve 60 to be moved to a further open position, but if an excess of water is being supplied and the material within the pan becomes softer, the energy required to rotate the shaft will be less and consequently the valve 66 will be moved to a further closed position, thereby providing means whereby the proper amount of water may be supplied 75 to the clay to form a mixture of the proper consistency.

75 This provides means whereby if one of the tile machines is thrown out of operation, the pugging action will also be stopped, and the water at the same time shut off, the feeding blades 73 of that particular unit also being thrown out of operation as before described.

80 It will be seen that this provides means whereby one or a number of tile cutters may be thrown into or out of operation with a single wet pugging pan, without changing the consistency of the mixture.

85 It will be seen that this provides means whereby a single feed hopper may be made to supply material to a pugging mechanism, which in turn is so arranged that neither one or a number of tile machines may receive material therefrom, and material will be supplied in right quantities and properly mixed regardless of whether one machine is in operation or the entire number.

90 It will further be seen that I have provided improved means whereby water will be automatically supplied to the mixture so that material will be fed to the tile machine having the proper plasticity.

95 I claim as my invention:

100 1. In a device of the class described, a pugging pan, a pugging mechanism within said pan, means for delivering material to be pugged to said pan, means for continuously supplying water to said material within the pan, means for driving said pugging mechanism, the quantity of water supplied being automatically controlled through the amount 105 of power required to operate said pugging mechanism.

110 2. In combination, a hopper, a feed table 115 to receive material from said hopper, a pugging wet pan, a pugging mechanism for said pan, means for operating said pugging mechanism, means for feeding material from said table to said pan, and means for 120 continuously supplying water to the material fed to said pan, the quantity of water supplied to said pan being automatically controlled by the consistency of the material within the pan.

125 3. In a device of the class described, a pugging pan, a pugging mechanism within said pan, means for supplying material to be pugged to said pan, means for conducting water continuously to the material with- 130

- in said pan, a valve for controlling the water for said water supply, an electric motor for driving said pugging mechanism, an electric circuit for supplying current to said motors, 5 said circuit including an electric magnet, means controlled by the variation of the current and said electromagnet for operating said valve, said parts being so adjusted and arranged that any variation in the current load for said motor required to operate the pugging mechanism will open and close said valve in a proper amount so that the mixture in the pan will be of uniform consistency.
- 10 15 4. A movable pugging pan, a shaft arranged above and transversely with the movement of said pan, a series of blunger knives for said shaft arranged in alternate and opposite directions and in a common plane, means for rotating said shaft, means for throwing the last said means into and out of operation, the last said means including means whereby the shaft will be stopped with the blunger knives resting in 20 25 a plane substantially parallel to said pan.
5. In a device of the class described, a movable pan, a shaft arranged above and transversely with the movement of said pan, a blunger blade for said shaft having its outer end curved and slightly eccentric with the center of said shaft, means for moving said pan at a fixed speed, means for rotating said shaft at such a speed that the end of said blade will travel at a slightly different speed than the said pan and to move closely thereto so that as it engages material fed to said pan, a combined crushing and dragging action will be imparted to the material by the curved end of said blade.
6. A tile cutter including a rotary cutting mechanism provided with a series of cutting wires, means for conveying pugged material to said tile machine, means for operating said tile cutter and said conveying means, and means controlled through the breaking of any one of said wires for throwing the last said means out of operation.

Des Moines, Iowa, June 10, 1924.

HALVER R. STRAIGHT.
